UNITED STATES PATENT OFFICE

JOHN WITTEMANN, OF LOS ANGELES, CALIFORNIA

SWINGING DRAPERY SUPPORT FOR CIRCLE-HEAD WINDOWS

Application filed July 26, 1930. Serial No. 470,843.

The somewhat general installation of circle-head windows in building operations as conducted as the present time, has created a demand for a swinging drapery support which would conform to the contour of the window, and be susceptible of easy association therewith.

The present invention resides in a specially constructed drapery supporting bar, curved 10 in side elevation so as to conform to the curvature of the window, such bar comprising a bowed strip, preferably of wood, to which the draperies can be easily attached, and a correspondingly curved metal strip, arranged 15 within the bow of the wooden or other strip, and secured thereto by novel fastening means, so as to constitute a rigid structure, incapable of deflection in any of its ordinary uses.

At one end of the curved drapery supporting bar, means are provided through special features of construction, for supporting the bar in its position of association with the window, and yet permitting the curved drapery supporting bar to be freely swung 25 away from the window, when occasion therefor arises.

The curved drapery supporting bar is constituted as a strip of thin flexible material, rectangular in cross section, with its wider 30 faces extending at a right angle to the plane of the window frame. To support and retain the said strip in its correct curved relation, a thin metal strip is bent edgewise according to the desired radius, and to the bent metal 35 strip the flexible strip first mentioned is firmly attached, so as to unite the two elements in fixed relation with each other.

In the foregoing, I have outlined the nature and purpose of my invention, which I 40 will now describe in detail and point out the novelty thereof in the appended claims.

In the drawings:

Figure 1 is a view showing the upper part of a circle-head window in phantom, and my 45 improved drapery support in the relative position which it occupies when associated with such a window.

Fig. 2 is an end elevation of the structure, looking from the right of Fig. 1.

Fig. 3 is a view of my improved structure,

looking upwardly toward the same, and showing in full line section parts of the window construction shown in phantom in Fig. 1.

In the drawings the numeral 10 indicates the frame of a window construction provided with a circle-head 11, of arcuate outline in elevation, such as is now being quite generally used in building operations.

In order to permit the support in a symmetrical manner of the draperies associated with the window, I provide a drapery supporting bar having an arcuate configuration closely approximating that of the circle-head window. In embodying my invention in a practical form, I take a strip of metal of suitable width and thickness, and of the necessary length, and bend such strip in the direction of its width, so as to produce a curved piece having the desired radius. The immobility of the material of which the edgewise curved metal strip is formed, causes it to retain the relatively fixed shape into which it is bent.

I then take a strip 13 of freely flexible material, preferably wood, of rectangular cross section, and bend such strip 13 over the outer edge of the curved metal strip 12, allowing the margins of the strip 13 to project at equal distances from the sides of the strip 12. The assembly in the position described of the strips 12 and 13, may be easily effected through the use of any simple holding mechanism, and when so assembled, I unite the strips 12 and 13 by means of clamps 14 formed from short strips of metal, and bent into the shape shown at the left of Fig. 3, so as to provide a narrow open loop of a depth and width just sufficient to receive the metal strip 12, and fit snugly thereover. The opposite projecting ends of the clamp 14 are perforated for the reception of fastening devices in the form of screws or bolts, engaging both the ends of the clamp and the strip 13 at opposite sides of the metal strip 12, so as to maintain the strip 13 in permanent position, after the holding mechanism for the strips 12 and 13 has been released. A clamp 14 at each end of the structure will ordinarily be sufficient to maintain the bent strips 12 and 13 in fixed relation.

To sustain the drapery supporting bar in position upon the window frame, I provide a metal bracket which may have the construction shown in Fig. 2, it having a base 15 to 5 rest against and be attached to the framework at one side of the window, such base being formed with an outwardly bowed portion 16, to provide clearance for a moulding, if the latter be used. Extending outwardly from 10 the base 15 are arms 17 and 18, united at their free ends by a portion 19, which serves to brace the arms 17 and 18 and maintain them against displacement.

In connection with the clamp 14 at one end 15 of the curved drapery supporting bar, I use an angular plate, one flange of which extends vertically as at 20, and the other flange of which extends horizontally as at 21, in Fig.

1. The vertical flange 20 of the angular 20 plate is aligned with the cooperating clamp 14, and is secured thereto by means of the bolts or screws which unite the parts, as previously described. The flange 21 of the angular plate is slotted through as at 22, for 25 the reception of a brace or strut 23, formed from a flat metal strip, passed through the perforation and extending some distance above and some distance below the said flange. The upper end 24 of the brace 23 is bent so 30 that such bent end will make a long contact with the inner edge of the curved metal strip

12. A clamp 25, having the shape of the clamp 14, but having its narrow loop elongated sufficiently to receive both the end 24 35 of the brace 23 and the strip 12, is attached to the curved strip 13 through screws or bolts, as before described, and maintains the upper end of the brace and the curved strip 12 firmly in an edge to edge contact.

40 The flange 21 of the angular plate is bored at a point between the perforation 22 and the angle of the plate, and a registering bore is provided in the arm 17 of the bracket. The flange 21 is seated on the arm 17, and a pivot 45 pin 26 is passed through the said bores so as to connect the parts. The lower end of the brace 23 is bent oppositely to the end 24, as at 27, and brought into engagement with the under side of the arm 18 of the bracket. 50 Both the end 27 of the brace and the arm 18 of the bracket are provided with bores aligned with the bores of the flange 21 and arm 17, and a pivot pin 28 is inserted in the bores in the parts 18 and 27 so as to connect the same. 55 The pivotal mounting of the drapery supporting bar permits it to be swung away from the window, to afford access to the window when desired, as is frequently the case when casements are employed.

60 The brace 23 performs an important function in the operation of the device, in that it resists any tendency of the drapery supporting bar to sag under the weight carried thereby, and serves always to maintain the fixture in its apportioned relation to the

circle-head of the window. The flange 21 of the angular piece, through its connection with the brace 23, serves as a stay for the brace 23 and retains it always in a relatively fixed position in the assemblage.

Having thus described my invention, what I claim and desire to secure by Letters Patent of the United States, is:

1. A swinging drapery support for a circle-head window, comprising a flat metal strip curved edgewise to conform to the contour of the window, a bent wooden strip overlapping the outer curve of the said metal strip, and clamps engaging the metal strip and secured to the flat wooden strip to maintain the angular cross-sectional arrangement of the associated metal and wooden strips.

2. A swinging drapery support for a circle-head window, comprising a flat metal strip curved edgewise to conform to the contour of the window, a bent wooden strip overlapping the outer curve of the said metal strip, clamps engaging the metal strip and secured to the flat wooden strip to maintain the angular cross-sectional arrangement of the associated metal and wooden strips, means for pivotally supporting the curved composite bar at one end, and a brace for sustaining the said bar against deflection, the said brace constituting part of the pivotal support for the bar.

In testimony whereof, I have signed my name at Los Angeles, this 13th day of June, 1929.

JOHN WITTEMANN.
